UNITED STATES PATENT OFFICE.

BEN K. FORD, OF OAK PARK, ILLINOIS, ASSIGNOR TO AMERICAN CAN COMPANY, OF NEW YORK, N. Y., A CORPORATION OF NEW JERSEY.

POURING-SPOUT AND CONTAINER.

1,266,671.

Specification of Letters Patent. Patented May 21, 1918.

Application filed April 10, 1915. Serial No. 20,369.

To all whom it may concern:

Be it known that I, BEN K. FORD, a citizen of the United States, residing in Oak Park, in the county of Cook and State of Illinois, 5 have invented a new and useful Improvement in Pouring-Spouts and Containers, of which the following is a specification.

This invention relates in general to pouring spouts for containers and has for its object broadly the provision of an improved 10 pouring spout which when closed will rest flat against the upper end of the container and which may be opened to pouring position by pure pivotal movement.

15 A principal object of this invention is the provision of a pouring spout which may be formed of a single sheet of suitable material and then operatively positioned on a container by merely inserting it in place, the 20 parts being so constructed and arranged as to interlock under ordinary usage without danger of separation and without danger of misplacement. This feature is important, as it insures the provision of an economical 25 package in that no operations are necessary upon the spout after it is in place. It also permits the filling of the can or container through the dispensing opening after the package is otherwise ready for the market.

30 A further object of the invention is the provision of a pouring spout of the character described which will be exposed to view and of such simple construction and operation that no particular instructions need 35 accompany the package in which it is incorporated to enable it to be readily used by the ultimate consumer. Packages provided with these pouring spouts are intended for particular use in the marketing of 40 salt, sugar, coffee and other household materials. Simplicity of construction and operation is particularly desirable in devices of this character.

45 Other objects and advantages of the invention will be apparent as it is better understood from the following description when considered in connection with the accompanying drawing illustrating a preferred embodiment thereof.

50 On the drawing,

Figure 1 is a section through a container and spout embodying my invention showing the spout in closed position;

55 Fig. 2 is a similar view showing it in open position;

Fig. 3 is a fragmentary perspective view of the container before the spout is positioned;

Fig. 4 is a partial top plan view after the spout is positioned; and

Fig. 5 is a perspective view of the pouring spout embodying my invention.

For the purpose of illustrating my present invention I have shown it embodied in a pouring spout 6, operatively positioned on 60 a container 7, filled with any suitable powdered or granular substance 8 which, for convenience of description, may be considered to be salt. In the present instance, the container 7 is of cardboard paper or other 65 fibrous material, although it will be manifest that containers may be constructed of any desired form or material. In the present instance an aperture 9 is provided through the top wall 10 of the container. This aperture is of trapezoidal form, having two converging sides 11 and parallel ends 12 and 13. The sides 11 are extended back of the body of the end 13 in recesses 14 so that the wide end 13 forms a short tongue extending into 70 the opening provided in forming the aperture. The pouring spout shown in perspective in Fig. 5 consists of a single portion 15 of superficial form approximating that of the aperture 9 except that its wide edge 16 75 is formed to fit over the tongue or lip 13 and its front or narrow end is extended to form a lip 17 for a purpose to be herein-after set forth. The width of the central portion 15 is substantially the width of the 80 opening. From each side of the central portion a wing 18 extends downwardly. This wing extends from inwardly of the lip 17 to beyond the wide end of the central portion. The portions 19 of the wings back of the 85 wide edge 16 are cut away so as to form hinge notches at 20 so that the upper edges of these notches of the wings may be engaged beneath the inner surface of the top 10 as shown in Fig. 1. In other words, the hinge 100 portions of the wing members are adapted to engage the inner surface of the container wall when the spout is closed (Fig. 1) and the extremities of the wing members are adapted to engage the inner surface of the 105 container wall when the spout is open (Fig. 2). These notches of the extensions form a pivotal connection between the spout and container and the opposite edges 21 of the wings 18 are curved to engage the front edge 110

of the opening 9, of the container, at the narrow end 12 of the said opening, throughout the opening and closing movement of the spout, so as to maintain said hinge engagement of the notches with the rear edge of the container opening. Stops 22 are provided at the lower ends of the wings 18 to engage the under face of the end 10 of the container to restrain further opening movement of the 10 spout when it has arrived at open position.

The spout may be formed by suitably cutting a blank sheet and then bending it along the lines indicated at 23. It may be positioned by merely pushing the spout 15 downwardly into place, this movement being accompanied toward its end with a slight rear movement into final position by reason of the engagement of the curved edges 21 with the front edge 12 at the opening. There 20 is no tendency in a spout of this character to become dislodged in use, as in opening it the finger or extension 17 is engaged and upward movement thereafter tends only to swing the spout to open position. It may 25 of course be readily worked out of the opening if deliberate intention is present to move the spout.

It is thought that the invention and many 30 of its attendant advantages will be understood from the foregoing description, and it will be apparent that various changes may be made in the form, construction and arrangement of the parts without departing from the spirit and scope of the invention 35 or sacrificing any of its material advantages, the form hereinbefore described being merely a preferred embodiment thereof.

I claim:

1. A hinged pouring spout for containers

having wing members formed with extensions to the rear of the line of hinging and with hinge notches to engage directly with the edge of an opening of a container, said wing members being arcuate to maintain said notches in engagement with such edge. 45

2. A hinged pouring spout for containers consisting of a central member which forms the bottom of the spout and is adapted to serve as a closure for the container, and two wing members which form the sides of the 50 spout, said wing members being formed with hinge notches contiguous to the central member adapted to engage directly with the edge of an opening of the container and said wing members being arcuate to hold the hinge 55 notches in engagement with such edge, and having extensions to the rear of said notches, a lip to engage on the outside of the container when the spout is closed and stops to engage within the container to limit the 60 opening of the spout.

3. The combination of a container having an opening into which extends a tongue 13 forming a hinge notch at each side of said tongue, and a spout having wing members 65 formed with extensions to the rear of the line of hinging and with hinge notches to engage directly in the notches of the said opening, said wing members being arcuate and said spout having means for limiting its 70 opening and closing.

Signed in the presence of two subscribing witnesses.

BEN K. FORD.
